ware

Application February 2, 1939, Serial No. 254,204

6 Claims. (Cl. 91—48)

This invention relates to the art of coating sheet materials and has particular reference to the art of coating flexible webs made of paper or similar material.

In general, the invention may be considered to be in the nature of a modification of the prior invention of John R. Fanselow as disclosed in his application for United States Patent filed February 2, 1938, Serial No. 188,369, Method and apparatus for coating sheet material, which application has been assigned to the assignee of this application. The said Fanselow application discloses the use of a vacuum chamber through which the web is propelled and to which web, either before or after it enters the vacuum chamber, there is applied a liquid coating which is doctoring or leveled off as or before the web passes out of the vacuum chamber. In the Fanselow application, such doctoring or leveling off of the coating is effected by the use of a stationary doctoring blade or bar which is so spaced from the coated surface of the web as to provide a relatively narrow slit or suction gap through which atmospheric air is sucked by the vacuum effect within the chamber. Such atmospheric air entering the vacuum chamber has the effect of leveling off the coating and also of removing any excess coating which may have been applied to the web.

The principal objects of the present invention are to provide, in a system of the general character herein described, an improved doctoring or air gap arrangement which will permit of the more efficient use of vacuum, which will reduce the volume of air which is required to be pumped in order to maintain the required degree of vacuum within the vacuum chamber; to provide an arrangement which will enable the mechanical manipulations to be more readily and more quickly effected; to provide a system and apparatus which may be more easily controlled and by which a more uniform coating may be produced with greater certainty and facility; to provide an apparatus of the character described which will be virtually self-cleaning, wherein breakage of the web may be reduced to a minimum, and wherein such breaks as do occur cause a minimum amount of inconvenience and lost production; to provide an apparatus which will be simple and inexpensive to design, construct and install, and which can be operated efficiently and economically; and in general to provide an improved apparatus of the character referred to.

In the drawings, which illustrate a preferred embodiment of the invention:

Fig. 1 is a diagrammatic elevation of the invention as applied to a Fourdrinier paper machine in order to apply a suitable surface coating to both sides of the paper web before the latter leaves the paper machine;

Fig. 2 is an enlarged side elevation of one of the coating units shown in Fig. 1;

Fig. 3 is an enlarged sectional elevation of certain of the parts shown in Fig. 2 together with other associated instrumentalities;

Fig. 4 is a perspective view of the vacuum chamber through which the web is propelled; and

Fig. 5 is a fragmentary sectional side elevation similar to Fig. 3, but showing the apparatus arranged for the application of coating material to the web within instead of outside of the vacuum chamber.

Referring to the drawings, the numeral 110 represents the web of paper which moves from left to right of Fig. 1. Said web as shown in Fig. 1 comes from the drying cylinders 111, passes through the first coating mechanism designated as a whole 112 where the top or felt side of the web is coated, and thence the web passes over a large drying cylinder 113 which dries the applied coating sufficiently to enable the coating to be touched or handled without injury. From the dryer 113, the web is conducted through a second coating apparatus 114 which serves to apply the coating to the under or wire side of the web. From the coating mechanism 114, the web passes around a second large drying cylinder 115 and thence to a set of ordinary drying cylinders 111a, if it is found necessary to effect any further drying of the web.

It will be observed that the apparatus, which in this instance comprises two units for treating both sides of the paper web, is in effect introduced 40 into the series of drying cylinders which constitute the drying section of a Fourdrinier paper machine. In some instances, it will be found advantageous, as shown in Fig. 1, to apply the coating before the paper has reached its final stage 45 of dryness. However, the apparatus may be employed to effect the coating of paper from which only a relatively small portion of moisture has been removed, or it may be used for coating paper which has passed the final drying stage. So far 50 as the coating operation is concerned, the apparatus can be made to operate satisfactorily upon papers having a very wide variance in moisture content, and, when properly adjusted, will apply various types and weights of coatings to different 55 types of webs.

In view of the fact that the coating units designated as a whole 112, 114 are of precisely similar construction but reversed in order to coat opposite sides of the web 110, only one of said coating units, namely the unit 112, need be specifically described. Said unit as shown best in Figs. 3 and 4 comprises a vacuum chamber which is formed by a set of four enclosure rolls 116, 117, 118 and 119. The roll 116 around which the web 110 is trained and by which the web is propelled through the vacuum chamber may be called a platen roll. The roll 117 immediately below the platen roll 116 may be termed the applicator roll for the reason that it cooperates with the paper and liquid coating supply instrumentalities to apply the liquid coating to the adjacent side of the web 110. Said function may be performed by the roll 117 whether the liquid coating is applied to the web within the vacuum chamber or before it enters the vacuum chamber.

The roller 119, although it does not actually engage the paper web 110, may nevertheless be called a doctor roll, in view of the fact that it constitutes one side of the gap or slit through which atmospheric air is sucked into the vacuum chamber and thereby functions to doctor off the applied coating so as to smooth or level off the same and to remove any excess coating material which may have been applied to the web.

Preferably the doctor roll 119 is rotated in such direction that that portion of its periphery which forms the orifice or suction gap will move upwardly; i. e. in the same direction as the movement of the web in the gap, and usually, in the case where four rolls are employed to form the enclosure for the vacuum chamber, it will be found advantageous to drive said doctor roll at a speed which will cause its periphery to move at the same speed as the rate of travel of the web. In most cases, I have found it advisable to equip doctor roll 119 with a positive drive so that it is not necessary to depend upon the frictional drag between the periphery of said roll 119 and the periphery of the sealing roll 118 with which roll 119 is in contact.

In practice, it is found that the surface of the doctor roll 119, as it emerges from the suction gap or orifice, carries a thin, quite uniform coating of the coating liquid, which coating is squeezed off in the nip between rolls 119 and 118 and may be collected and re-used in the equipment. If desired, a stationary doctor 119^a of the knife type may be applied to the periphery of the doctor roll 119 in order to clean off and collect the said liquid coating on its periphery and also in order to remove any grit or other foreign matter which may be carried up out of the orifice by the doctor roll 119.

A relatively narrow gap is obviously desirable in order to save pumping capacity. As indicating the type of gap which can be used with the described equipment, it may be said that with a web speed of from 200 feet to 700 feet a minute a paper web can be supplied with a satisfactory coating when the gap between the paper and the doctor roll measures between 10 and 20 one-thousandths of an inch, in connection with a vacuum equal to between 2 and 4 inches of mercury. The thickness of coating will naturally depend upon the character and consistency of the coating liquid, the spacing or width of the orifice, the speed of travel of the web, and the degree of vacuum.

The roll 118 is merely a sealing roll which 75

serves to close the space between the applicator roll 117 and the doctor roll 119. Preferably, at least one pair of the diagonally opposite rolls of the set of four which constitute the enclosure for the vacuum chamber are constructed of relatively soft rubber or similar material, so that an efficient seal between the cooperating rolls may be effected without the necessity of employing excessive pressure between the cooperating rolls.

The ends of the vacuum chamber are closed by means of end seals 120 which are provided with inwardly facing rubber parts which overlap the ends of the rolls and thereby prevent leakage 15 of air into the chamber. Air is withdrawn from the chamber by means of a relatively large pipe 121 which extends through the chamber from end to end and along its length is provided with a series of apertures 122 properly spaced and of the proper size to produce a uniform withdrawal of air across the entire width of the web. Said suction pipe 121 is connected at its ends to a pipe 123 which leads into a settling drum 124 connected by means of the pipe 125 to a vacuum 20 pump (not shown) of the required capacity.

In the case of the arrangement shown in Fig. 3 which shows the apparatus adapted for application of liquid coating to the web on the outside of the vacuum chamber, such application is effected as follows:

A pump 126 forces a supply of liquid coating through the pipe 127 into a distributing trough 128 which discharges through suitably spaced apertures into an application trough 129, the 35 inner side of which is open to the upper surface of the roll 117.

The pipe 130 is connected to a reservoir (not shown) of coating material and delivers to the pump 126 a sufficient amount of coating material to provide a coating of the required weight upon the web which is being treated, with sufficient additional coating material to supply any loss due to leakage or wastage. Any excess coating material which is removed through the suction pipe 121 is collected in the settling drum 124 and is returned to the pump through the pipe 131.

The rolls 116, 117, 118 and 119 are all mounted in suitable bearings provided with more or less conventional arrangements whereby the pressures between pairs of rolls or cooperating rolls can be conveniently regulated or adjusted according to the requirements of the apparatus and also whereby, if desired, any roll may be 50 swung away from the roll or rolls with which it cooperates so that the web may be manipulated by the operators as desired. For example, as shown in Fig. 2, the roll 118 is mounted on bearings which are arranged to slide in a frame 132 under the influence of a tension spring 133 which draws the bearings towards the axis of the roll 117. Said arm 132 is mounted to swing concentric with the axis of the roll 117 so that the roll 118 will always be in proper engagement with the roll 117, regardless of the angular position of the arms 132. Said arms 132 are adapted to be swung resiliently upward so as to bring the roll 118 in proper engagement with the doctor roll 119 by means of bell-crank arms 134 integral with the arms 132, the lower ends of the arms being drawn in the proper direction by cables 135 to which tension is applied by a spring or weight (not shown).

The bearings for the doctor roll 119 are similarly arranged to slide in arms 136 pivoted at 137

upon a stationary part of the machine. Said bearings are forced downwardly within the slide arms 136 by means of compression springs 138 so that there is the proper degree of contact between roll 119 and roll 118. The doctor roll 119 may be readily adjusted with reference to the web and platen roll 116, or it may be swung away from the platen roll 116 and the sealing roll 118 completely by means of cables 139 attached to the arms 136 and adjusted by a suitable traverse screw 140 operated by a hand-wheel 141.

In Fig. 5, I have shown the coating unit arranged for internal application of coating fluid. This is effected by eliminating the outside troughs 128 and 129 and connecting the end of the coating supply pipe 127 directly to the ends of a distributing pipe 142 which extends through and between the end seals adjacent to the nip between rolls 116 and 117. Said distributing pipe 142 is provided with suitable apertures 143 through which the coating fluid is directed into the nip and against the surface of the traveling web 110. If desired the internal distributing pipe 142 may be used in combination with the external trough 119. The presence or absence or extent of the internal pool depending upon conditions does not seem to be important.

In most cases, whether the liquid coating be applied inside or outside of the vacuum chamber, or both inside and outside, I have found it more convenient to supply and circulate a considerable excess of coating fluid, the thickness or weight of the ultimate coating being preferably regulated by adjustment of the doctor roll, or by regulation of the amount of vacuum within the chamber, or by both. However, in the application of certain types of coatings, it may be found desirable in certain instances to first regulate the doctor and the vacuum so as to provide a coating somewhat in excess of that which is desired and then to cut down the supply of coating material to an amount which will furnish a coating of the required weight. In the case of the outside application as shown in Fig. 3, the supply of coating to the web can be cut down by reducing the gap or increasing the pressure between rolls 116 and 117, while in the case of the apparatus shown in Fig. 5 such reduction in liquid supply may be effected by suitably controlling the flow through pipe 127.

The scope of the invention should be determined by reference to the appended claims, said claims being construed as broadly as possible consistent with the state of the art.

I claim:

1. Apparatus for coating webs which comprises a platen roll around which the web may be propelled, a doctor roll having its periphery spaced slightly from the web at a point where the web is supported by the platen roll and rotatably supported so that said spacing may be maintained constant independent of different angular positions of said doctor roll, means cooperating with said rolls to form a chamber through which the web is propelled while it is supported on the platen roll, means for applying a coating liquid to the traveling web on that side thereof which is presented towards the doctor roll and before the web passes between said rolls and out of said chamber, and means for withdrawing air from said chamber to create an inward suction between said rolls so as to level off said coating.

2. Apparatus for coating webs which comprises a platen roll around which the web may be pro-

pelled, a doctor roll having its periphery spaced slightly from the web at a point where the web is supported by the platen roll, a pair of rolls cooperating with each other and respectively with the platen and doctor rolls to form an enclosure forming part of a chamber through which the web is propelled while it is supported on the platen roll, means for applying a coating liquid to the traveling web on that side thereof which is presented towards the doctor roll and before the web passes between said rolls and out of said chamber, and means for withdrawing air from said chamber to create an inward suction between said platen and doctor rolls so as to level off said coating.

3. Apparatus for coating webs which comprises a platen roll around which the web may be propelled, a doctor roll having its periphery spaced slightly from the web at a point where the web is supported by the platen roll and rotatably supported so that said spacing may be maintained constant independent of the angular position of the doctor roll, means cooperating with said rolls to form a chamber through which the web is propelled while it is supported on the platen roll, means for applying an excess of coating liquid to the traveling web on that side thereof which is presented towards the doctor roll and before the web passes between said rolls and out of said chamber, and means for withdrawing air from said chamber to create an inward suction between said rolls so as to level off said coating and to reduce the said coating to the desired thickness.

4. Apparatus for coating webs which comprises a platen roll around which the web may be propelled, a doctor roll having its periphery spaced slightly from the web at a point where the web is supported by the platen roll, means for rotating said doctor roll so that its periphery adjacent the platen roll will move in the same direction as the direction of web propulsion, means cooperating with said rolls to form a chamber through which the web is propelled while it is supported on the platen roll, means for applying a coating liquid to the traveling web on that side thereof which is presented towards the doctor roll and before the web passes between said rolls and out of said chamber, and means for withdrawing air from said chamber to create an inward suction between said platen and doctor rolls so as to level off said coating.

5. Apparatus for coating webs which comprises a platen roll around which the web may be propelled, a doctor roll having its periphery spaced slightly from the web at a point where the web is supported by the platen roll and rotatably supported so that said spacing may be maintained constant independent of different angular positions of said doctor roll, means cooperating with said rolls to form a chamber through which the web is propelled while it is supported on the platen roll including a roller engaging and rolling upon said doctor roll, means for applying a coating liquid to the traveling web on that side thereof which is presented towards the doctor roll and before the web passes between said rolls and out of said chamber, and means for withdrawing air from said chamber to create an inward suction between said platen and doctor rolls so as to level off said coating.

6. Apparatus for coating webs which comprises a platen roll around which the web may be propelled, a doctor roll having its periphery spaced slightly from the web at a point where the web is supported by the platen roll, a pair of rolls

cooperating with each other and respectively with the platen and doctor rolls to form an enclosure forming part of a chamber through which the web is propelled while it is supported on the platen roll, means for rotating all of said rolls at substantially the same peripheral speed, means for applying a coating liquid to the traveling web

5 on that side thereof which is presented towards the doctor roll and before the web passes between said rolls and out of said chamber, and means for withdrawing air from said chamber to create an inward suction between said platen and doctor rolls so as to level off said coating.

WARREN GEORGE.
